(57) **CLAIM**

The ornamental design for a conduit hub, as shown and
described.

DESCRIPTION

FIG. 1 is an isometric view of our new design;

FIG. 2 is a first side view of the design of FIG. 1, with the
second side view being identical;

FIG. 3 is a front view of the design of FIG. 1, with the rear
view being identical;

FIG. 4 is a top plan view of the design of FIG. 1;

FIG. 5 is a bottom plan view of the design of FIG. 1;

FIG. 6 is an isometric exploded view of the design of FIG.
1; and,

FIG. 7 is a side view of the conduit hub shown in a position
of use in its environment.

The broken lines shown in the drawings illustrate portions of
the conduit hub and environment that form no part of the
claimed design.

The dash dot broken lines depict boundaries of the conduit
hub and form no part thereof.

The dashed broken lines depict portions of the conduit hub
and form no part thereof.
